BATHROBE PACKAGE

Filed March 3, 1927

Fig. 1,

Fig. 2,

UNITED STATES PATENT OFFICE.

LEO C. SAFIR, OF NEW YORK, N. Y.

BATH-ROBE PACKAGE.

Application filed March 8, 1927. Serial No. 172,220.

The present invention concerns garment packages, particularly for robes and the like, and has for its object the provision of an improved package.

Nearly all garments are made of materials which necessarily are pliable and non-rigid, thus giving rise to much difficulty in maintaining the garments in their proper array when not supported. This disarray into which they naturally fall under their own weight, as when in storage, on display, or in transit, detracts materially from their attractiveness to prospective purchasers. It has long been the complaint of garment manufacturers and merchandisers of garments, especially of those garments which depend upon an attractive or exceptionally neat appearance for their salability, that it was impossible to obtain any sort of device which could be depended upon to at least preserve the original neat and "smart" appearance of their products; particularly at that most important moment when they are displayed to prospective purchasers. In storage, shipping or display, no structure was available which could accomplish these results by use of a cheap article of such low cost that it could be thrown away after one use.

The object with which the present invention is primarily concerned is that of solving the problem of proper enclosure and protection and effective display by the employment of one or two simple co-operating members which can be made so cheaply and of such a cheap material that their replacement value is practically nil, and yet which are so sturdy and so constructed as to properly support the garment.

Further, it is an object of the present invention to provide means for attractively displaying a garment, such as a robe, in such a manner that its real neatness of shape and design will not be impaired by being in a container and may even be enhanced thereby, even though the package may be placed in positions and locations,—as in window displays, storage, or shipping,—which usually result in distorting, wrinkling, creasing, rumpling, or otherwise reducing the salability of the garment.

It is a further object of the present invention to conceal the presence of the means for causing and preserving the attractiveness, as the visible presence of such means

often prejudices prospective purchasers against the value of the merchandise.

The invention will be described in conjunction with the accompanying drawings, which illustrate, by way of example, a preferred embodiment thereof.

In these drawings:

Fig. 1 is a perspective view of the package, omitting the cover thereof; and

Fig. 2 is a perspective view of one of the elements of the package.

Referring now more in detail to the accompanying drawings, the package of the present invention shown in Fig. 1 comprises a container, box, or tray 1, preferably of card-board and of a general rectangular configuration. This container has a top or cover, not shown, for the usual purposes of protection and closure.

Within the container 1 there is provided a co-acting plate or sheet of card-board 2 of general rectangular configuration, almost as wide as the container, and somewhat shorter than the container. This member 2 is provided, from its upper edge 3, to a point considerably below its center, and at least sufficiently far below the center to extend below the lower opening 4 of the neck 5 of a robe, with a generally V-shaped incision or opening 6 whose edges are substantially parallel with and behind the inner edges of the V-neck of the robe, and thus the member 2 is completely concealed thereby.

There is thus formed on the member 2, a pair of rigid, non-folding, upstanding, sturdy arms 7, 7. These arms are of greater strength than almost any formation possible, because of the fact that all forces tending to collapse the arms 7, 7 are directed ultimately against the triangular bases 8 thereof. Hence, these rigid, upstanding arms act most efficiently to spread out the garment in the shoulders and trunk in a taut and an unusually neat manner and further preserve it in a smooth, attractive condition as long as it is in the package.

Further, the member 2 serves as a gage in making up the package, as its length is made to correspond to that of the outer portion of the garment which is most effective on display.

In making up the package, the member 2 is inserted in the upper part of the robe in such a manner that the arms 7 fit snugly

and securely in the shoulders at the shoulder-seam. The robe is then buttoned over the body-portion of the member 2, the arms of the robe are folded suitably behind it, 5 and the tails of the robe are folded upwardly and backwardly around the bottom edge of the member 2, which thus acts as a gage.

There are thus no visible means for 10 preserving the neat and attractive appearance of the garment, and yet the only way in which the garment can be disarranged is by disassembling the package. No clips, tabs, straps, holders, or the like are required, and there is no possibility of the garment sagging or distorting under its own weight 15 when in the package, or becoming creased and ruined while in storage, transit or display, and in all positions and attitudes of 20 the package, the garment is preserved against disarray. It is clear that cheapness is one of the outstanding advantages of the invention, and yet it is capable of successful use.

25 I claim:

1. A robe-package, comprising a container, a member therein having a body-portion provided with a pair of spaced up-standing arms, and a robe having its shoulders supported in a plane parallel to the bottom of the container by said arms, its trunk buttoned around the body-portion of 30 said member, and its skirts folded around the lower edge of said member to fit into said container.

2. A robe-package, comprising a container, a separate member therein having a body-portion of a substantially rectangular configuration, the upper portion of said 35 body being bifurcated and the lower portion of said body being solid, and a robe having its shoulders draped around said bifurcations, its trunk buttoned around said body-portion, and its skirts folded upwardly 40

around the lower edge of said member to fit 45 into said container.

3. A robe-package, comprising a container having a width at least one-half its length, a rigid, uncollapsible robe-form 50 of substantially rectangular configuration therein, substantially as wide as the container and slightly shorter than said container, said member having an opening extending from its upper edge into the body-portion of said form, forming two arms of 55 the upper portion and leaving the lower edge solid and straight, and a robe having its shoulders spread apart and supported in the plane of the bottom of said container by being draped about said arms, its trunk 60 buttoned around the body-portion of said form, and its skirts folded back and upwardly around the lower edge of said member to fit into said container.

4. A robe-package, comprising a container having a width at least one-half its length, a rigid, uncollapsible robe-form 65 of substantially rectangular configuration therein, substantially as wide as the container and slightly shorter than said container, said member having a V-shaped opening extending from its upper edge into the body portion of said form to a point 70 sufficiently distant from the upper edge of said form to render said form invisible 75 when the robe is folded around it, said opening forming two arms of the upper portion and leaving the lower edge solid and straight, and a robe having its shoulders spread apart and supported in the plane of the bottom of said container by being draped about said arms, its trunk buttoned around 80 the body-portion of said form, and its skirts folded back and upwardly around the lower edge of said member to fit into said container. 85

In testimony whereof I affix my signature.
LEO C. SAFIR.
